UNITED STATES PATENT OFFICE.

ANTON GRAF, OF WORCESTER, MASSACHUSETTS.

GAS-CONSUMER FOR FURNACES.

1,289,157.

Specification of Letters Patent. Patented Dec. 31, 1918.

Application filed March 28, 1918. Serial No. 225,226.

To all whom it may concern:

Be it known that I, ANTON GRAF, a citizen of the United States, residing at Worcester, in the county of Worcester and State of Massachusetts, have invented new and useful Improvements in Gas-Consumers for Furnaces, of which the following is a specification.

This invention is an improvement in gas consumers for furnaces and relates more particularly to devices for perfecting the combustion of gases in the combustion chamber.

In the burning of coal or other solid fuel a large part of the available heat energy is given off as various gases which, if unburned, do not yield up their heat, and in order to prevent this loss I provide means for creating a sheet or curtain of air and steam through which the gases must pass before they leave the combustion chamber. To attain this result I employ a series of jets or nozzles located on the bridge wall and arranged with no structure between the jets and the boiler, said jets being arranged on an arc of a circle, concentric with the boiler and having outlets arcuate in cross-section, which outlets are directed upwardly and rearwardly so as to produce a parti-conical curtain or sheet of air and steam directed against the bottom of the boiler. I have found in practice that it is advantageous to arrange a baffle wall near the rear of the boiler so arranged as to require the gases and the steam and air to pass downwardly from the bottom of the boiler before they leave the combustion chamber.

With these and other objects in view, which will appear as the description proceeds, my invention resides in the combination and arrangement of parts disclosed herein and claimed hereafter.

In the accompanying drawings, wherein similar parts are indicated by like reference characters,

Figure 1 is a vertical central section of a furnace embodying my invention,

Fig. 2 is a vertical section taken on line 2-2 of Fig. 1,

Fig. 3 is a side elevation of the preferred form of jet,

Fig. 4 is a rear view of the jet shown in Fig. 3,

Fig. 5 is a side elevation of a modified form of jet, 55

Fig. 6 is a rear view of the modified form of jet,

Fig. 7 is a diagrammatic view showing the outlet in the preferred form of jet, the jet being seen from the rear of the furnace, 60

Fig. 8 is similar to Fig. 7, showing the modified form of jet, and

Fig. 9 is a reduced section on line 9-9 of Fig. 1, showing a modified form of baffle wall. 65

Referring to the drawings, 10 indicates the boiler resting upon any approved form of setting 11 having a fire-box 12 with grate 13 and ash pit 14. The usual chimney 15, steam dome 16, bridge wall 17, and combustion chamber 18 are provided. 70

Located at the top of bridge wall 17 and embedded therein is a pipe 19, the outer end of which carries a bell 20 the top of which is open to the air. An injector 21 is mounted in the bell and receives steam from the dome 16, by means of which pipe 19 receives air and steam. Threaded into pipe 19 is a series of nozzles or jets 22 (one only of which is shown in Fig. 1), having outlets 23, which face rearwardly and upwardly of the boiler. As shown in the drawings, the tops of these nozzles project somewhat above the bridge wall, but I do not wish to be limited to this construction as any arrangement which will permit the air and steam to pass from said nozzles rearwardly and upwardly is within the scope of my invention. 85

As shown in Figs. 4 and 7 the outlet 23 is curved, being preferably arcuate convexly with respect to the boiler, while Figs. 5, 6 and 8 show outlets arcuate concavely with respect to the boiler. Either construction

provides a series of arcuate outlets arranged on an arc so that the mixture of air and steam issuing from the outlets forms a sheet or curtain, which is part of a hollow cone the axis of which is substantially the axis of the boiler. This form of curtain is produced by having the tops of the jets at a slight angle, as shown in Fig. 1, so that the air and steam is directed rearwardly from the bridge wall and upwardly to the bottom of the boiler, thus requiring the gases to pass through the air and steam to insure perfect combustion. It will be noted that where 100

90

95

105

- the jet as indicated in Fig. 4 is used a larger area of contact with the gases is provided. Also, the entire bottom of the boiler is exposed to the fire-box and combustion chamber, there being no walls or other heat insulating structure to absorb heat and shield a portion of the boiler, in this way letting the gases be acted upon by the air and steam without being interfered with by brick work 5 between the boiler and bridge wall. Again, the jets are equidistant from the boiler, insuring uniform heating and assisting the draft instead of obstructing it, as in some proposed furnaces. By making the face of 10 the jet as shown in Fig. 4 concave the air and steam issues therefrom more compactly and with less spreading than is the case with the jet shown in Fig. 6, where the face is convex.
- 15 20 It is general experience that the hottest part of the gas flame is somewhat above the point where the gases and oxygen unite and it is with this in mind that the baffle walls are constructed so that the flames may 25 reach upwardly and have the hottest parts thereof strike the boiler. Therefore, located at the rear of the boiler is a baffle wall indicated in Fig. 1 at 25, having an outlet 26 at the bottom thereof spaced from the 30 boiler, said baffle wall being so constructed as to require gas, smoke, and steam and air to pass through the outlet 26 as indicated by the arrows in Fig. 1, thus further insuring the mixing of the gases and air.
- 35 Reference to Fig. 2 shows the baffle wall 25 as extending downwardly from the boiler to the bottom of the combustion chamber, the outlet 26, shown in dotted lines, being formed centrally thereof and in the lower 40 part of said baffle wall. In smaller boilers it may be desirable to employ a baffle wall 27 constructed as indicated in Fig. 9, said baffle wall being substantially concentric with the boiler.
- 45 50 Actual tests show that the employment of my improved jets and the baffle wall, when added to ordinary boilers, increases the amount of water evaporated in the boiler and decreases the amount of coal consumed.
- 55 What I claim is:
1. A gas consumer for furnaces comprising a boiler, a bridge wall the top of which is substantially concentric with the boiler, a series of spaced jets arranged on the bridge wall, means to supply a mixture of steam and air to said jets, the jets having arcuate outlets substantially concentric with the boiler and opening toward the rear of 60 the boiler, and a rear baffle wall extending downwardly from the boiler and having the bottom thereof substantially concentric with the boiler, said jets facing upwardly and rearwardly to direct the mixture of steam and air against the boiler in front of 65 the baffle wall, whence said mixture and the gases pass downwardly under said baffle wall.
2. A gas consumer for furnaces comprising a boiler, a bridge wall the top of which is substantially concentric with the boiler, a series of spaced jets arranged on the bridge wall, means to supply a mixture of steam and air to said jets, the jets having arcuate outlets opening toward the rear of 70 the boiler, and a rear baffle wall extending downwardly from the boiler and having the bottom thereof substantially concentric with the boiler, said jets facing upwardly and rearwardly to direct the mixture of steam and air against the boiler in front of 75 the baffle wall, whence said mixture and the gases pass downwardly under said baffle wall.
3. A gas consumer for furnaces comprising a boiler, a bridge wall the top of which is formed on an arc of a circle substantially concentric with the boiler, a series of spaced jets arranged on the bridge wall, said jets having upwardly and rearwardly extending 80 faces provided with arcuate openings all of which lie on an arc substantially concentric with the boiler, a rear baffle wall extending downwardly from the boiler and having the bottom substantially concentric with the 85 boiler, and means to supply the jets with a mixture of steam and air which issue from said spaced jets toward the boiler and is then directed downwardly to pass under the baffle wall.
4. In a gas consumer for furnaces comprising a boiler, a bridge wall substantially concentric therewith and a rear baffle wall depending from the boiler and having the bottom thereof substantially concentric with 90 the boiler, the combination of a series of jets arranged on the bridge wall, each jet having an upwardly and rearwardly extending face formed as a part of a cylinder and having therein an opening having opposite 95 edges substantially concentric with the boiler, and means to supply said jets with a mixture of steam and air.
5. In a gas consumer for furnaces comprising a boiler, a bridge wall substantially 100 concentric with the boiler and a rear baffle wall depending from the boiler and having the bottom thereof substantially concentric with the boiler, the combination of a pipe 105 embedded in the bridge wall and constituting a supply of steam and air, and a series of jets, each having a straight shank to connect with the said pipe and having the upper portion thereof offset, said offset portion 110 having a rearwardly facing portion formed as part of a cylinder and inclined with respect to the boiler, said portion of the offset having therein an opening opposite 115
- 120
- 125

edges of which are substantially concentric with the boiler.

6. A gas consumer for furnaces comprising a boiler, a bridge wall, a pipe in said bridge wall to supply a mixture of steam and air, a series of jets connected to said pipe and having rearwardly extending faces provided with arcuate outlets, and a rear baffle wall extending downwardly from the

boiler, the top of the bridge wall, the supply pipe, the outlets in the jets and the bottom of the baffle wall all being substantially concentric with the boiler.

Signed at Worcester, county of Worcester and State of Massachusetts, this 25 day of 15 March, 1918.

ANTON GRAF.
